UNITED STATES PATENT OFFICE.

TOM V. KELLEBREW, OF HAMBURG, ARKANSAS.

HAY PRESS.

Application filed June 6, 1921. Serial No. 475,493.

To all whom it may concern:

Be it known that I, TOM V. KELLEBREW, a citizen of the United States, residing at Hamburg, in the county of Ashley and State of Arkansas, have invented new and useful Improvements in Hay Presses, of which the following is a specification.

This invention relates to improvements in hay presses and has for an object the provision of a press of simple construction, which is capable of being manually operated.

Another object is the provision of a press of this type, whose operating means is so constructed as to deliver a maximum amount of power to the baling plunger, so that the press may be operated by two men with a relatively small amount of labor.

Another object is the provision of a press in which the plunger may be held at the limit of its inward stroke, so as to hold the bale under compression as long as desired.

A further object of the invention is the provision of a novel means for holding the discharge door of the press in closed position in a manner to resist the action of the press, when in operation.

With the above and other objects in view, the invention further includes the following novel features and details of construction, to be hereinafter more fully described, illustrated in the accompanying drawings and pointed out in the appended claim.

35 In the drawings:—

Figure 1 is a side elevation of a baling press constructed in accordance with the invention, the parts being in the position occupied when the plunger is at the limit of its outward stroke.

Figure 2 is a plan view of the same.

Figure 3 is a vertical longitudinal sectional view showing the plunger at the inward limit of its stroke and locked against outward movement.

Figure 4 is an end view of the press.

Figure 5 is a transverse sectional view.

Referring in detail to the drawings, wherein like characters of reference denote corresponding parts, the press is shown as including a base which is formed of a frame, the latter comprising longitudinally extending side bars 10 and a center bar or beam 11, all of which are connected by lower cross bars or sills 12 and upper cross bars 13. Extending from this frame is an

extension base which includes spaced parallel beams 14 which project from one end of the frame just described, being positioned upon opposite sides of the center beam 11, which, for this purpose extends beyond the end of the frame. The beams 14 are removably connected to the beam 10 by transverse bolts 15 and a spacing block 16 is secured between the beams 14 near the outer end of the beam 11. A slot 17 is thus formed between the beams 14 which extends from the spacing block 16 to the outer ends of the beams.

Mounted upon the transverse bars 13 of the base frame is a baling box 18, each side of which is formed to provide longitudinal spaces or slots, as usual in devices of this character. Each end of the box 18 is open, while the top of the box is also provided with an opening which is surrounded by downwardly flared inclined walls or plungers 19 to provide a filling hopper for the box. One end of the box has hingedly secured thereto as shown at 21, a door 22 for closing this end of the box and in order to hold the door in closed position, there is provided a bar 23 whose lower end is pivoted within a slot formed in the central beam 11 upon a pivot pin or bolt 24. The bar 23 extends upwardly and centrally of the door and has pivotally secured to its upper end as at 25, one end of a latch bar 26. The latch bar 26 is provided with a shoulder 27 which is adapted to engage a keeper 28 secured upon the baling box 18. This provides a strong and durable means for holding the door 22 in closed position in a manner to resist the pressure of the operation of the press, yet permits the ready disengagement of the latching means for the purpose of discharging a completed bale.

The outer ends of the beams 14 are preferably supported upon a transverse sill 29, while secured between the beams 14 near their outer ends is a standard 30. A brace 31 has its upper end connected to the standard and its lower end secured between the beams 14, both said brace and standards being removably secured in position by means of bolts 32.

Pivotedly secured between the beams 14 upon a pivot bolt 33, is the lower end of a power arm or lever 34, while pivotally connected to this lever 34 as at 35, is one end of a rod or bar 36. The opposite end of the bar 36 is secured to a plunger 37 which

operates within the baling box 18 and serves to compress the hay into bales when the power lever 34 is operated. The plunger 37 has extending from its upper edge a plate 38 which acts to prevent hay passing in through the hopper from falling upon the outer side of the plunger, the said plate 38 providing a bottom for the hopper when the plunger is in its inmost position. Any hay within the hopper at this time will remain therein until the plunger has been moved outward, whereupon the hay will pass downward into the box.

Mounted upon the baling box between the standards 39 is a cylinder 40, whose outer ends are connected to crank arms 41 so as to provide a windlass. Wound upon the cylinder 40 is a cable 42 whose opposite ends are secured to the upper end of the power lever 34. This cable 42 also passes around the pulley or shaft 43 which is located at the upper end of the standard 30, the said standard also carrying a bumper block 44 for contact by the power lever 34. Extending from this bumper block and connected to the outer end of the standard 30 are spaced rods 44' which provide a guide for the cable 42.

When the windlass is operated, the cable 42 will be simultaneously wound and unwound and rock the power lever upon its pivot and through the connecting rod 30 will operate the plunger as will be readily understood.

In order to hold the plunger at the limit of its inward stroke so as to hold the bale under compression as long as desired, there is pivotally connected to the baling box 18 a loop or bail 45, which is adapted to engage a hook 46 carried by the power lever, as is clearly illustrated in the drawings.

After a bale has been completed, the plunger is moved outward and further hay fed into the box, the said bale having been previously tied. The discharge door is then released, whereupon an inward movement of the plunger will force the bale outward through the end of the box.

The invention is susceptible of various changes in its form, proportions and minor details of construction and the right is herein reserved to make such changes as properly fall within the scope of the appended claim.

Having described the invention what is claimed is:—

A hay press embodying a baling box having a feed opening therein, a plunger movable within said box, a power lever spaced from one end of the box, a rod connecting the plunger and power lever, whereby movement of the latter will operate the plunger, means for operating the power lever, and a bail pivotally secured to the box and engageable with a hook carried by the power lever for holding the latter against downward movement.

TOM V. KELLEBREW.
